FENCE POST MOLD

Eugene B. Miller, Chicago, Ill.

Application April 29, 1950, Serial No. 159,036

1 Claim. (Cl. 25—118)

An object of my invention is to provide mold means, made of inexpensive material, that may remain an integral part of the fence post.

A further object of my invention is to provide molding forms made of inexpensive material that can be shipped flat, and hence reduce the cost of transportation.

A still further object of my invention is to provide a bottom cup means which may be utilized in connection with the prefabrication of the fence posts comprising my invention.

Other objects, and advantages resident in my invention will become apparent from an examination of the following parts comprising my invention.

Invention will become apparent from an examination of the accompanying drawings, which bear further elucidation in the ensuing description, wherein like numerals represent like parts, and in which;

Fig. 1 is a perspective view showing the preparation of the cavity in the soil, and the setting of the mold therein preparatory to pouring a concrete post at the particular situs in the ground.

Fig. 2 is a perspective view showing how a barbed wire fence may be strung up on the post formed in Fig. 1.

Fig. 3 is a transverse cross-sectional view taken substantially along the lines 3—3 of Fig. 2.

Fig. 4 is a vital element of the mold structure comprising my invention shown in knock-down construction ready for transportation.

Fig. 5 is a fragmentary perspective view showing the bottom part of the mold formed with a reinforcement preparatory to pouring concrete thereinto.

Fig. 6 shows another form for transportation of the vital elements of the mold form used in constructing my fence post invention, and shows a multiple number thereof rolled up so that they can be peeled off as needed.

Fig. 7 is a view partly in cross section bringing out the specific feature of a mold formation for constructing, or prefabricating, fence posts which can be ultimately shipped in transit to the locale needed.

Referring to the various views, in Fig. 1, an auger generally designated 8 and provided with a cutting blade 9 having offset cutting edges 10 may be utilized for making a series of openings or cavities 12 in the ground 11. The said cavities 12 are adapted to receive the form for pouring a concrete fence post generally designated 13 and which, as indicated in Fig. 5, is provided with a bottom portion 18 so as to prevent the concrete from seeping into the soil and producing an irregularity at the top surface 25 of the fence post.

It will be noted, in Fig. 4, that the cylindrical element 14 may be shipped knocked down flat, and that it is provided with a straight edge 21, two straight edges abutting the same and a fourth edge which is provided with a crimped lip portion 16 parted by notched portions 17 so as to facilitate rolling the element 14 into the cylindrical shape indicated in Fig. 1. The edges of the sheet 14 may be held in place by a strip 15 and by retaining collars 31.

The elements 14, 18 and 31 compositely form a mold and an integral part of the post 25 entitled a seasoning decomposable wrapper, and the said elements 14, 18 and 31 are made preferably of cardboard of suitable gauge and it is to be noted that the elements 14 are also provided with indented portions 19 as indicated in Fig. 7 for locating or providing recesses in the concrete post 25 in which the wires 26 and 27 will lodge firmly after attachment.

The fence proper is preferably made up of a number of wires 26 strung along horizontally and which have barbs on them for reasons which are readily obvious; the said lines 26 being located in the cavity 19 at the rear of the form at 28. Whereas the same are held in place on the post by U-shaped wires 27, the legs thereof being coiled as at 30 to fasten them to the lines or wires 26. The U-shaped elements 27 have certain portions thereof 29 located with an oppositely positioned notch formed on the mold.

The mold being of paper, and being economical to use, is placed right into the opening 12, the concrete is poured and allowed to set after which lines 26 and the U-shaped elements 27 may be attached thus forming the fence proper.

In the form illustrated in Figs. 1-5 the cylindrical form 14, the bottom 18, and the rings 31 are not removed from the concrete post thus formed; they are not stripped from the post, allowing the elements to ultimately deteriorate the same, hence permitting gradual seasoning of the concrete post 25, by preventing too much moisture from reaching the concrete post 25, subsequently to pouring operations.

In the course of time, the forms 14 may deteriorate in which event the fence will not be affected in the least. Should it be desired to ship the elements 14 in rolled-up fashion, they 50 may be rolled up as indicated at 20 with the straight edge 21 ready to peel off as shown in Fig. 6, to be subsequently formed to the proper shape, secured with rings 31, and reinforced by a bottom 18. Or it may be desired to prefabricate 55 posts in which event I provide a cap 23 of

metal, or other suitable material, having a bottom 24 so as to permit casting the post therein. After the post solidifies, the cap 23 may be removed and used for producing other posts. The cap 23 does not become part of the post; it is merely a part of the form which does not remain with the post structure.

It is believed that the drawings, and the foregoing description, clearly disclose the nature of my contribution to the art of fence post structure, and it is believed that those familiar with the patent art will have no difficulty in discerning the novelty thereof.

It is to be understood that changes may be made in the construction and in the combination and arrangement of the several parts, provided that such changes fall within the scope of the appended claim.

Having thus disclosed and revealed my invention, what I claim as new and desire to secure by Letters Patent is:

A mold for pouring and forming concrete forms therein, comprising a sheet of paper-like material having crimped lip portions on one of its shorter edges, and provided with spaced apart indented portions adjacent the other of its shorter

edges, the said sheet when formed to cylindrical configuration resulting in a tubular element having an interior lip portion on its lowermost extremity and a pouring opening at its top, a bottom element secured within the confines of the cylinder formed and resting on the said interior lip portion, and paper ring means slidably secured at predetermined spaces about the outer surface of the said cylinder.

EUGENE B. MILLER.
